Fig. 7.

Fig. 8.

Fig. 9.

Fig. 10.

Fig. 11.

FIGS. 1, 2, 3, 4, 5 and 6 respectively are a side elevation, an end elevation looking from the left of FIG. 1, an end elevation looking from the right of FIG. 1, a top plan view, a bottom plan view, and a perspective view of a lighter or similar article embodying my new design.

FIG. 7 is an end elevation of a modified form of the lighter shown in FIG. 1. FIGS. 8, 9, 10 and 11 are respectively a side elevation of FIG. 7, an end elevation as seen from the left of FIG. 8, a top plan view of FIG. 7 and a perspective view of FIG. 7.

This is a continuation-in-part of my earlier filed application Serial No. 65,350, now abandoned.

I claim:

The ornamental design for a lighter or similar article, substantially as shown and described.
